Primary Examiner — Marissa J Cash*Assistant Examiner* — Rebecca Tsehay(74) *Attorney, Agent, or Firm* — Bookoff McAndrews,
PLLC(57) **CLAIM**

The ornamental design for a vaporizing device, as shown as described.

DESCRIPTION

FIG. 1 is a perspective view of the vaporizing device;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

Features shown in broken lines form no part of the design as claimed.
